STRINGED MUSICAL INSTRUMENT

Walter J. Pelensky, 19C Manheim Gardens,
Philadelphia, Pa. 19144

Filed Sept. 28, 1970, Ser. No. 25,211

Term of patent 14 years

Int. Cl. D17—03

U.S. Cl. D56—1

Fig. 2

Fig. 1

Fig. 3

FIG. 1 is a face view of a stringed musical instrument, specifically a plucked Ukrainian bandura, showing my new design;

FIG. 2 is a left side elevation view; and

FIG. 3 is a right side elevation view thereof.

Portions of the drawings are shaded to indicate contrast in appearance.

I claim:

The ornamental design for a stringed musical instrument, as shown and described.
